EGBERT DE HAAN, OF GRAND RAPIDS, MICHIGAN

SURFACE FINISHER FOR TURNED WORK

Application filed October 13, 1927. Serial No. 225,914.

The present invention relates to surface-finishing for work turning in a lathe; and its object is, generally, to provide mechanism of that character improved as hereinafter appears; and more particularly, to provide such a mechanism having separately movable and controllable operating parts; and further, to provide improved mounting means for the work-engaging elements.

10 This and any other and more specific objects hereinafter appearing are attained by, and the invention finds preferable embodiment in, the structure hereinafter particularly described in the body of this specification and illustrated by the accompanying drawings, in which—

Figure 1 is a front view of a lathe to which my surface-finisher is applied;

Figure 2 is a right-hand end view thereof;

20 Figure 3 is a top plan view of the same;

Figure 4 is a vertical transverse sectional view thereof taken on line 4—4 of Figure 3; and

Figure 5 is a vertical transverse sectional view of means for mounting the work-engaging elements, taken on line 5—5 of Figure 3.

In the structure illustrated by these drawings, my surface-finisher is shown applied 30 to the bed 1 of a lathe having the live head stock 2 and dead head stock 3 on which rotates the work piece 4 being turned. A lever comprising a parallel pair of members 5, 5, is fulcrumed at 6, 6 in connection with the 35 lathe's bed, and has the part or handle 7 (connecting said members) for operating said lever. An arm comprising a parallel pair of members 8, 8 is mounted at 9, 9 swingably on said lever 5 and carries at its free inner 40 end the mounting for the finishing element, which mounting comprises a pair of bars 10, 11, preferably of metal, extending parallelly with the rotary axis of the work piece 4. The lower one, 11, of these bars has an 45 upwardly extending rear flange 12 so positioned relatively to the rear edge or side of the upper bar 10 that, when these bars are pressed together, they will clamp an abrasive or sanding sheet 20 between these flanges and 50 between the lower surface of the upper bar

and upper surface of the lower bar as particularly well seen in Figure 4. These bars 10, 11 are held in clamping engagement with such sheets between them, as by the springs 14 pressing them together. The metallic 55 lower bar 11 has downwardly extending front and rear flanges 15, 16 and is formed with holes 17 through which pass screws 18 extending between these flanges and threaded in a lowermost wooden bar 19 for clamping 60 between these bars 11 and 19 resilient fibrous members, as the broom straws 21 which underlie and yieldingly support the abrasive sheet in contact with the work.

A second lever 22 is fulcrumed at 23 on the 65 lever 5 on an axis parallel with the fulcrum axis 6 of the lever 5. A link 24 is pivotally mounted at 25 and 26 on the inner end of lever 22 and the free end of the arm 8 respectively. A foot lever 27 fulcrumed at 28 on the floor 70 beneath the lathe is connected with the outer end of the lever 22 by a link 13 so that pressure by the foot of the operator on the pedal end 29 of lever 27 will swing the abrasive sheet 20 upwardly and into contact with the 75 turning work piece 4; and the handle 7 of lever 5 may be grasped by the hand of the operator to move the abrasive sheet forward and backward in a direction transverse to its vertical movement caused by the foot 80 lever 27.

It will thus be seen that these two movements of the abrasive element may be carried on and controlled independently of each other, one being accomplished by the operator's foot and the other by his hand.

It will also be seen that the bars 10, 11 are so formed as to very securely clamp and hold the abrasive sheet 20 and its resilient support 21.

The joints or pivotal connections 6, 9, 23, 25, 26 or some of them, may be made loose enough, or the parts 5, 8, 22, 24 may have sufficient spring quality, to permit the bars 10, 11 to be slightly oscillated endwise in the machine's 95 operation, in order to obliterate sanding marks on the work.

The invention being intended to be pointed out in the claims, is not to be limited to or by details of construction of the particular 100

embodiment thereof illustrated by the drawings or hereinbefore described.

I claim:

1. In combination with a lathe, a surface-finisher for work in the lathe comprising: a lever fulcrumed in connection with the lathe's bed on an axis disposed parallelly with the rotary axis of the work; an arm mounted on said lever swingably toward and away from the rotary axis of the work; a lever fulcrumed on the first-mentioned lever on an axis disposed parallelly with the fulcrum axis of the first-mentioned lever; means connecting one end of the second-mentioned lever with the free end of the arm; a surface-finishing element carried by the arm and adapted to be moved by the second-mentioned lever into and out of contact with the work turning in the lathe, and to be moved by the first-mentioned lever in a transverse direction.
2. In combination with a lathe, a surface-finisher for work in the lathe comprising: a lever fulcrumed in connection with the lathe's bed on an axis disposed parallelly with the rotary axis of the work; an arm mounted on said lever swingably toward and away from the rotary axis of the work; a lever fulcrumed on the first-mentioned lever on an axis disposed parallelly with the fulcrum axis of the first-mentioned lever; means connecting one end of the second-mentioned lever with the free end of the arm; a surface-finishing element carried by the arm and adapted to be moved by the second-mentioned lever into and out of contact with the work turning in the lathe, and to be moved by the first-mentioned lever in a transverse direction; a lever; a link extending between the third-mentioned lever and the second-mentioned lever for moving the latter by the former.

In testimony whereof I have hereunto set my hand at Grand Rapids, Michigan, this 10th day of October, 1927.

EGBERT DE HAAN.
